UNITED STATES PATENT OFFICE.

EDWIN B. PIERCE, OF BROOKLYN, NEW YORK.

FEEDING DEVICE FOR BOOK-SEWING MACHINES.

Application filed September 12, 1919, Serial No. 323,251. Renewed April 30, 1927.

My invention relates to improvements in feeding mechanism for book sewing machines. It has been customary to place the signatures, which are to be sewed together to form a book successively on a receiver which moves so rapidly that the signature could not be placed on it while in motion; the movement of the receiver being necessarily interrupted to allow time for placing the signature. The principal purpose of my invention is to provide a series of continuously moving receiving arms each of which will engage in given position with a single punching saddle, the receiving arms moving at such speed that the signature may be placed on them without interrupting or retarding movement.

Referring to the accompanying drawings, Fig. 1 shows in side elevation, parts being broken away, a part of a book sewing machine illustrating an embodiment of my invention. Fig. 2 is a view looking from left to right at one of the receiving arms of the series showing the upper right hand corner of Fig. 1. Fig. 3 is an enlarged detail, looking from right to left, at the sprocket wheel and spider mechanism shown in the upper right hand corner of Fig. 1. Fig. 4 is an enlarged cross sectional detail of the upper portion or cross bar of the saddle.

Referring to Fig. 1, 5 indicates one of the frames of the machine of which two are provided identical in outline held together by a cross frame. The frames are provided with suitable bearings supporting the drive shaft and the cam shaft 8. On the cam shaft is mounted and secured a crank 33, having a crank pin and roller 34, which moves in the variably curved slot 35" of the crank 36". 37" is a rockshaft in suitable bearings in the frame 5 to which the crank 36 is secured. Mounted and secured on the rockshaft 37 are two similar arms 38, each having an extension 39 and carrying a counter weight 40. In suitable bearing in arms 38 is a rockshaft which supports the signature carrying and perforating saddle. This saddle consists essentially of the upright side bar 41 and the hollow cross bar, within which is the vertically movable slide 42 carrying a series of punches suitably spaced for perforating the signatures preparatory to sewing.

At a suitable position in each of the side bars 41 of the saddle, a wrist pin is secured, carrying a roller 35' adapted to move in a

groove 36' formed in the guide plate 37' which is secured to the frame 5. The crank 33 turning in the direction indicated moves the saddle upwards from the position shown, the path of the apex of the saddle being determined by the groove 36'. This upward movement continues until the apex of the saddle is in contact with the throat plate of the sewing device where it remains at rest until the signature is engaged and secured by the sewing mechanism. The saddle then moves downward to its lowest position and immediately upward again traveling the entire distance between its highest and lowest positions in either direction without interruption.

7 indicates a bracket secured by bolts to the frame 5 and an auxiliary bracket secured by bolts to the side of the bracket 7. The hubs of the brackets are concentric and bored through to provide bearings for the rotary parts of the feeding device. 13 indicates a spider having a number of arms each carrying a receiving plate 22. 11 indicates a sprocket wheel secured to the hub of the spider 13. 10 is a sprocket chain and 9 a sprocket wheel which is secured to the shaft 8. The number of teeth on the sprocket wheel 11 must have a ratio to the number of teeth on the sprocket wheel 9 equal to the number of receiving plates carried by the spider 13. If three plates are used, as illustrated, and the diameter of wheel 11 is three times the diameter of wheel 9, it is evident that the saddle moves from the position shown through one complete cycle returning to the same position again. The plate shown as in contact with the apex of the saddle, will have advanced through one-third of its rotation and the next succeeding plate will have reached the point of contact with the saddle. As the signatures after being placed on the plates 22 are held in place by gravity until they are lifted by the saddle, it is evident that the plates 22 must always stand at the same angle of elevation, that is, in the same position relative to a horizontal line. To accomplish this, a planetary gear mechanism is provided as illustrated in detail in Figs. 2 and 3.

Referring to Fig. 3, 14 indicates the hub of the spider 13 which extends through the bearing in bracket 7 and through the hub of sprocket wheel 11. This wheel 11 is secured to the hub 14 by any convenient means

such as the binding screw 16. 12 indicates a shaft which extends through a central bore of the hub 14 and is secured in the auxiliary bracket 7' by the binding screw. Thus 5 spider 13 will turn with the sprocket wheel 11 while the shaft 12 is stationary. 17 is a stationary gear mounted on the shaft 12 and secured by the binding screw 19. In the spider 13 are fixed studs 13' on which are 10 loosely mounted gears 20 which are in mesh with the stationary gear 17. The frame 35 is provided with suitable bearings, through which the shaft 36 extends, and also a projecting hub or sleeve 37 to which is secured 15 the gear 21. 22 is one of the plates on which the signatures are placed by the operator. It is secured to the frame by screws or rivets as indicated. The gear 21 has the same pitch diameter as the central gear 17 20 and is in mesh with one of the intermediate gears. If the spider 13 be driven around the shaft 12, plate 22 will be carried in a circular path around gear 17 but because of the reversing effect of the intermediate gear will 25 maintain the same angle of elevation in all positions as shown in Fig. 1. The angle of elevation of the plate 22 may be varied or adjusted by loosening the binding screw and turning the gear 17 slightly to right or 30 left as required. The signature supporting edge of the plate 22 travels in a circular path eccentric to the shaft 12 and concentric of shaft 36. In order to prevent actual contact and consequent abrasion of the plates 35 while passing at the intersecting point, the upper edge of each plate is cut away where the points of the punches would otherwise strike as shown in Fig. 2.

The folded signatures are sharply and 40 permanently creased at the fold and have a tendency to collapse on the receiving plates and a spreading or opening device is required to hold the signature away from the lower side of the plate and provide a sufficient angle for the saddle to enter the signature 45 without interference.

Referring to Fig. 2, a shaft 38' is held in bearings in the frame 35. 25 are supports fastened to the shaft 38' and a rod 39' is fastened to the upper ends of the supports 25. 24 is a pin inserted in the shaft 38' and having its upper end shaped as a gear tooth and entering a corresponding groove in the hub of the lever 28. 29 is a stationary cam secured to the guide plate 37' having its working face formed on a separate piece which is adjustable by means of the fulcrum 30 and the slot 31 and binding screw 32. By the rotation of the spider 13 the projection 55 of the lever 28 is pressed against the cam 29, forcing it to turn backward around the hub and by reacting against the pin 24 moving the rod outward and downward from the plate 22 and holding the lower edge 60 of the signature in suitable position for the

saddle to enter. A coiled spring 26 is provided which presses against the support 25 tending to keep the rod in its normal position against the lower side of the receiving plate, and returning it to that position, 70 when the lever 28 is released from the cam 29.

To secure the proper alignment of the signatures on the several plates and to determine their position in relation to the 75 punches, adjustable gauges 42 are provided as illustrated in Fig. 2. In practice the various signatures are opened slightly and slipped successively over the feed plates from which they are taken automatically by the 80 saddle as described.

Of course it will be understood that various modifications may be made in the construction and arrangement of parts without departing from the spirit of the invention 85 as claimed.

I claim:

1. In a book sewing machine, a saddle adapted to receive and support signatures and having movable supports, guides to determine the path in which it travels, a feeding device comprising a reel rotating about a horizontal axis and carrying several arms or plates adapted to receive and transfer signatures, means for actuating the saddle 90 and for rotating the reel so proportioned that the saddle shall pass through as many complete cycles of its movement as there are receiving plates on the reel during each complete rotation of the reel. 100

2. A signature feeding device comprising a reel rotating about a horizontal axis and carrying several plates adapted to receive and transfer signatures, means for rotating the reel, and means for maintaining all of the said plates at a uniform and constant angle of elevation. 105

3. A signature feeding device comprising a reel rotating about a horizontal axis and carrying several plates adapted to receive 110 and transfer signatures, means for rotating the reel, means for maintaining all of the said plates at a uniform and constant angle of elevation, and means for changing or adjusting the angle of elevation as required. 115

4. In a book sewing machine a reel mounted to rotate on a horizontal axis carrying a plate adapted to enter between the leaves of a folded sheet of paper to support it by contact with the fold, a vertically movable saddle adapted to enter between the leaves of the folded sheet carried by the plate, means for rotating the reel to bring the plate carrying the folded sheet over the saddle, and means for moving the saddle 120 upward to enter between the leaves of the folded sheet to lift it from the plate. 125

5. In a book sewing machine a reel mounted to rotate on a horizontal axis carrying a plate adapted to enter between the leaves 130

- of a folded sheet of paper to support it by contact with the fold, a vertically movable saddle adapted to enter between the leaves of the folded sheet carried by the plate, 5 means for rotating the reel to bring the plate carrying the folded sheet over the saddle, means for moving the saddle upward to enter between the leaves of the folded sheet to lift it from the plate, and means 10 carried by the reel for separating the leaves of the folded sheet carried by the plate to facilitate entrance of the saddle.
6. In a book sewing machine a reel mounted to rotate on a horizontal axis carrying a 15 plurality of plates each adapted to enter between the leaves of a folded sheet of paper to support it by contact with the fold, a vertically movable saddle adapted to enter between the leaves of the folded sheet carried by the plate, means for rotating the reel to bring the plates carrying the folded sheet successively over the saddle, and means for moving the saddle upward to enter between the leaves of the folded sheet to lift 20 it from the plate so timed with reference to the rotation of the reel as to cause the saddle to lift the folded sheet from each plate successively.
7. In a book sewing machine a reel carrying a plurality of plates each adapted to enter between the leaves of a folded sheet of paper to support it by contact with the fold, a vertically movable saddle adapted to enter between the leaves of the folded sheet carried by the plate, means for rotating the reel to bring the plates carrying the folded sheet successively over the saddle, means for moving the saddle upward to enter between the leaves of the folded sheet to lift 25 it from the plate so timed with reference to the rotation of the reel as to cause the saddle to lift the folded sheet from each plate successively and means carried by the reel for separating the leaves of the folded sheet 30 to facilitate entrance of the saddle.
8. In a book sewing machine a reel mounted to rotate on a horizontal axis, a shaft carried by the reel carrying a plate adapted to enter between the leaves of a folded sheet 35 to support it by contact with the fold, a saddle adapted to enter between the folds of a sheet to support it, and means for rotating the reel to bring the folded sheet over the saddle in such a position that the saddle will enter between the leaves of the sheet and means for 40 rotating the shaft carrying the plate to withdraw the plate so as to leave the folded sheet on the saddle, and means carried by the reel for separating the leaves of the folded sheet carried by the plate to facilitate entrance of the saddle.
9. In a book sewing machine a reel mounted to rotate on a horizontal axis, a shaft carried by the reel carrying a plate adapted to enter between the leaves of a folded sheet to support it by contact with the fold, a saddle adapted to enter between the folds of the sheet to support it, means for rotating 45
- the reel to bring the folded sheet over the saddle in such position that the saddle will enter between the leaves of the sheet, means for rotating the shaft carrying the plate to withdraw the plate so as to leave the folded sheet on the saddle, and means carried by the reel for separating the leaves of the folded sheet to facilitate entrance of the saddle.
10. In a book sewing machine a reel 75 mounted to rotate on a horizontal axis, a shaft carried by the reel carrying a plate adapted to enter between the leaves of a folded sheet to support it by contact with the fold, a vertically movable saddle adapted to enter between the folds of the sheet to support it, means for rotating the reel to bring the folded sheet over the saddle in such a position that the saddle will enter between the leaves of the sheet, means for 80 moving the saddle upward to enter between the leaves of the sheet carried by the plate and means for rotating the shaft carrying the plate to withdraw the plate so as to leave the folded sheet on the saddle. 90
11. In a book sewing machine a reel a shaft carried by the reel carrying a plate adapted to enter between the leaves of a folded sheet to support it by contact with the fold, a vertically movable saddle adapt- 95 ed to enter between the folds of the sheet to support it, means for rotating the reel to bring the folded sheet over the saddle in such a position that the saddle will enter between the leaves of the sheet, means for 100 moving the saddle upward to enter between the leaves of the folded sheet carried by the plate, means for rotating the shaft carrying the plate to withdraw the plate so as to leave the folded sheet on the saddle, and means carried by the reel for separating the leaves of the folded sheet carried by the plate to facilitate entrance of the saddle. 105
12. In a book sewing machine a reel mounted to rotate on a horizontal axis comprising spider arms having a shaft mounted to rotate therein, a plate carried by the shaft adapted to enter between the leaves of a folded sheet of paper to support it by contact with the fold, a gear on the shaft, a stationary gear serving as a rack to cause the plate carrying gear to rotate the shaft carrying the plate, a saddle adapted to enter between the leaves of the folded sheet carried by the plate vertically movable in a path passing through the path of movement of the outer edge of the plate, means for rotating the reel and means for reciprocating the saddle. 110
13. In a book sewing machine a reel 125 mounted to rotate on a horizontal axis comprising spider arms having a shaft mounted to rotate therein, a plate carried by the shaft adapted to enter between the leaves of a folded sheet of paper to support it by 130

contact with the fold, a gear on the shaft, a stationary gear serving as a rack to cause the plate carrying gear to rotate the shaft carrying the plate, a saddle vertically movable adapted to enter between the leaves of the folded sheet carried by the plate in a path passing through the path of movement of the outer edge of the plate, means for ro-

tating the reel, means for reciprocating the saddle, and means carried by the spider arms 10 for separating the leaves of the sheet carried by the plate to facilitate entrance of the saddle.

In testimony whereof I hereunto affix my signature.

EDWIN B. PIERCE.
